UNITED STATES PATENT OFFICE.

CHARLES F. LEFEVER, OF PLYMOUTH, MICHIGAN, ASSIGNOR TO DAISY MANUFACTURING COMPANY, OF PLYMOUTH, MICHIGAN, A CORPORATION OF MICHIGAN.

POPGUN.

Application filed April 19, 1926. Serial No. 103,118.

The invention relates to guns and refers more particularly to pop guns. The main objects of the invention are to simplify the construction of parts necessary to perform the required functions and also to arrange the parts so that they may be readily and quickly assembled.

With these as well as other objects in view the invention resides in the novel features of construction as more fully hereinafter set forth.

In the drawings:—

Figure 1 is a side elevation of a gun embodying my invention;

Figures 2 and 3 are vertical longitudinal sections through the gun;

Figures 4 and 5 are side elevations of the abutment member and trigger assembly;

Figure 6 is a cross section on the line 6-6 of Figure 3;

Figure 7 is a plan view of Figure 4;

Figure 8 is a plan view of the blank for forming the barrel and frame of the gun.

As shown, the type of gun to which my improvements are applied is that in which air compressed by the movement of a spring pressed plunger will eject a cork or stopper from the muzzle end of the barrel. The barrel and frame of the gun are formed from an integral sheet metal blank A, shown in Figure 8, having a portion B which is bent into cylindrical form with overlapping edge portions and wider portions C which form the frame. These portions C have opposite inturned flanges forming the bottom of the frame and cut away at D to provide an opening for the trigger. The muzzle end of the barrel has its overlapping edges united by spot welding, this being sufficient to hold said portion in cylindrical form. At the other end, the frame portion may be sprung apart for the insertion of the trigger, as hereinafter described.

Within the barrel is placed the plunger E having a shank F. G is a coil spring having one end abutting the plunger and H is a member for abutting the other end of the spring. This abutment member is formed from a flat blank of sheet metal having a portion H' which fits vertically within the barrel and a reduced portion H² projecting from the portion H' to fit within the spring and forming shoulders H³ against which the spring abuts. The plunger shank F extends within the spring and at one side of

the abutment member H, being provided with a transverse or hooked inner end F' which passes through a slot H⁴ in the abutment member. The slot H⁴ has the front portion of its length extending parallel to the axis of the barrel and the rear portion first deflected upward and then at right angles downward to form a sear H⁵. The shank is drawn backward by a slotted link I which engages the hooked end F' and at its rear end is pivotally attached at J to the stock K which latter is pivoted on a pin L extending through the rear portions of the frame. The trigger O is formed from a sheet metal blank having a depending ring portion O', a shank portion O² which passes through the slot D and a portion O³ which normally extends longitudinally below the slot H⁴. The abutment member H has a laterally bent ear H⁶ formed with a T head and the member O is slotted at O⁴ for engagement with this ear. The arrangement is such that by placing the trigger at an angle it may be readily assembled upon the ear by passing the ear into the slot, while in the normal position of the trigger the ear acts as a pivot for the trigger. P is a sheet metal member of U-shaped cross section attached to the stock and extending forward therefrom to embrace the frame and to form bearings for the pivots L and J.

With the construction described the parts may be easily assembled by first engaging the spring with the plunger G on the shank F, then inserting the reduced portion H² of the abutment member H in the rear coils of the spring so that the latter abuts against the shoulders H³ and at the same time engaging the hooked end F' through the slot in the link I and the slot H⁴ in the abutment member. The trigger O is also engaged with the ear H⁶ of the abutment member. The plunger, spring, trigger and abutment member are then all inserted within the barrel, the abutment member being fashioned to extend vertically within the frame and having an upwardly extending lug H' located in the slot D' at the breach end of the barrel. The link I has its slot engaged with the hooked end F' and lies adjacent to the abutment member H. The pin L is inserted through registering apertures in the member P, the frame portions C and the rear portion of the abutment member H and the pin J is inserted through the link I.

and the member P. When these pins are inserted the assembling is complete and will operate as follows:

When the gun is broken down by the movement of the stock upon the pivot L, this, through the pin J, will draw the link I rearward carrying with it the hooked end F' of the plunger shank. At the completion of this movement the link I extends at such an angle that it will be drawn around the curve in the slot H⁴ and will engage the sear H⁵. The stock may then return to normal position, the slot in the link permitting this movement without interference with the hooked end F'. The pulling of the trigger O will cause that member to pivot on the ear H⁶ raising the rear end of the portion O³ and displacing the hooked end F' from engagement with the sear H⁵. This permits the recoiling of the spring and the forward movement of the plunger G, which is stopped by the hooked end F' contacting with the front end of the slot H⁴.

The construction is exceedingly simple inasmuch as the barrel, frame, abutment member, link I and trigger O are of sheet metal stampings dispensing with the necessity of any other machine work. The parts are also easily assembled and are held in engagement solely by the pins J and L.

To hold the link I from disengagement from the hooked end F' the front end portion of said link is bent to slightly offset the same so that this portion by its contact with the abutment member will hold the shoulder of the slot of the link in full engagement with the hooked end F'. The abutment member H in addition to its engagement with the pin L has a shoulder H⁶ which bears upon the rear end of the barrel and extends into the opening D² formed in the portions C to assist in holding the abutment member in vertical position.

What I claim as my invention is:—

1. In a gun, a barrel and frame formed from an integral sheet metal blank, the barrel portion being bent into cylindrical form having overlapping portions, and the frame being formed of oppositely turned aligned flanges forming the bottom thereof with an opening at one point for the passage of a trigger, and a trigger insertable in said frame and in engagement with said aperture by springing apart said aligned flanges.

2. In a gun, the combination with a barrel and frame, of a plunger assembly insertable within said barrel and frame and comprising a plunger, a hooked shank therefor, a spring surrounding said shank, a sheet metal member having its forward end forming a spring abutment and slotted for engagement with the hook of said shank, said sheet metal member being fashioned to fit vertically and centrally within the frame, a slotted link lying parallel to said sheet metal member

and engaging the hook of the shank, a stock member, a pivot for attaching said stock member to said frame and sheet metal member and a pin for attaching said link to said stock member.

3. In a gun, the combination with a barrel and frame, of a sheet metal member arranged vertically and centrally within said barrel and frame the forward end thereof forming a spring abutment, said member also having a longitudinal slot therein and a downwardly extending portion at its rear end forming a shoulder or a sear, a plunger within said barrel, a spring for said plunger engaging said abutment, a plunger shank extending parallel to said sheet metal member and having a hooked portion extending through said slot, a link engaging said hook for retracting the same through said slot and into engagement with said sear and a trigger pivotally attached to said member and having a portion for disengaging said hook from said sear.

4. In a gun, the combination with an integral barrel and a frame, and a stock pivotally attached thereto, of a plunger assembly insertable as a unit within said barrel and frame comprising a plunger, a shank extending rearward therefrom and having a hooked end, a spring sleeved upon said shank, a sheet metal member for extending vertically and centrally within said barrel, the forward end thereof forming a spring abutment and said member being also provided with a longitudinal slot with which said hook is engaged, said slot terminating at its rear end in a downwardly extending portion forming a shoulder or sear, a trigger pivotally attached to said member and adapted to disengage said hook from said sear, a link arranged parallel to said member pivotally engaging said hook at its forward end and said stock at its rear end whereby the breaking down of the stock will retract said plunger shank and engage the same with the sear.

5. In a gun, the combination with a barrel having an integral frame and a stock pivotally attached thereto, of a plunger assembly comprising a plunger shank extending therefrom having a hook at its rear end, a spring upon said shank, a sheet metal member for vertically and centrally engaging said barrel and frame forming a spring abutment at its forward end being provided with a longitudinal slot for engaging the hook of said plunger shank, said slot terminating at its rear end in a down-turned portion forming a shoulder or sear, a pivot for connecting said stock and frame passing through said sheet metal member and forming an anchor therefor, a trigger pivotally attached to said sheet metal member and a link pivotally engaging the hook of said shank and the pivot in said stock for the purpose described.

6. In a gun, a sheet metal member insertable vertically and centrally within the barrel and frame having its forward end forming the spring abutment, its rear end engaging the pivot between the frame and stock and its intermediate portion having a longitudinally extending slot for engaging the hooked end of a plunger shank, said slot terminating at its rear end in a downwardly 10 extending portion forming a shoulder or sear, and a trigger pivotally attached to said member having a portion for engaging the plunger shank from said sear.
7. In a gun, a sheet metal member insertable vertically and centrally within the barrel and frame having a reduced portion at its forward end for engaging the spring and forming an abutment therefor, a rear portion engaging the pivot between the barrel 20 and the stock, an intermediate portion with a longitudinal slot for engaging a hook on the plunger shank, said slot terminating at its rear end in a down turned portion forming the shoulder or sear, a laterally bent ear 25 on the portion beneath said slot and a trigger slotted for engagement with said ear to form a pivotal connection therewith, said trigger having a portion for disengaging the hook from the sear.
8. In a gun, a sheet metal member insertable vertically and centrally within the barrel and frame, its forward end forming a spring abutment, its rear end engaging the pivot for connecting the frame and stock, 30 and its intermediate portion having a longitudinally extending slot terminated at its rear end in a down turned portion, a trigger pivotally attached to said member on one side thereof, a plunger shank having
- its hooked rear end engaging said slot and a link for engaging said hooked end arranged on the opposite side of said sheet metal member.
9. In a gun, a sheet metal member insertable vertically and centrally within the barrel and frame having its forward end forming a spring abutment, its rear end engaging the pivot between the frame and stock, and its intermediate portion having a longitudinally extending slot terminating in a 40 down-turned portion at its rear end, a sheet metal trigger having a portion engaging an ear on said first mentioned sheet metal member and a portion extending beneath the down turned end of said slot and a slotted link arranged on the opposite side of said first mentioned member.
10. In a gun, a combined barrel and frame formed from an integral sheet metal blank, a stock a pivot for attaching said stock 45 to said frame, and a sheet metal member insertable vertically and centrally within said frame and barrel, its rear end engaging said pivot, its forward end forming a spring abutment and its intermediate portion being 50 slotted to form a guide for the plunger shank and a sear, a trigger pivotally attached to said member on one side thereof, a plunger shank having a hooked rear end for engaging said slot and a slotted link for 55 connecting said plunger shank and said stock arranged on the opposite side of said central sheet metal member, said link having a laterally deflected portion for guiding the same within the barrel and maintaining engagement with said hooked shank.

In testimony whereof I affix my signature.
CHARLES F. LEFEVER.
